UNITED STATES PATENT OFFICE.

CHARLES D. DALLAS, OF WINNETKA, ILLINOIS.

WINDING ARBOR.

Application filed December 31, 1921. Serial No. 526,279.

To all whom it may concern:

Be it known that I, CHARLES D. DALLAS, a citizen of the United States, residing at Winnetka, in the county of Cook and State 5 of Illinois, have invented certain new and useful Improvements in Winding Arbors, of which the following is a description.

My invention belongs to that general class of devices known as arbors, and relates particularly to a winding arbor for winding or coiling any desired material for any desired purpose. The invention has among its objects the production of a device of the kind described that is simple, convenient, efficient, compact, durable and satisfactory for use wherever found applicable. More particularly it has an object the production of an arbor of the kind described which will enable the material to be wound or coiled 10 substantially tight or firm, wound to the desired size, and quickly and easily removed from the arbor and without distorting the coil. It also has as an object the production of an arbor in which several coils may be wound simultaneously where the arbor is of sufficient length for the purpose. Many other objects and advantages of the construction herein shown and described will be obvious to those skilled in the art from 15 the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a sectional view of my improved 40 device;

Fig. 2 is an enlarged cross sectional view taken substantially on line 2—2 of Fig. 1;

Fig. 3 is a plan view of the inner side of one of the arbor parts;

Fig. 4 is a plan view of a portion of the shaft; and

Fig. 5 is a plan view showing a portion of Fig. 3 enlarged to more clearly show the construction.

50 In the drawings, in which the preferred

embodiment of the invention is shown, it may be mentioned that I have illustrated an arbor adapted for winding strip metal, it being understood, however, that the material to be wound may be such as is desired. 55 As shown, 1 represents a shaft of the desired size and driven in any suitable manner, preferably by power, the same being rotatably supported by a bearing 2 of any desired machine, forming no part of the present invention. The shaft 1 carries the arbor parts 3, of which there may be any desired number, three parts being shown, which may be contracted or expanded as desired. 60

As shown, the shaft 1 is provided with projecting parts 4 having inclined faces, the same in the construction shown being constructed in pairs, with a space 5 between the same, and they may be countersunk as indicated at 6' at the reduced end or base of the inclined faces, as indicated at 6, for the purpose hereinafter referred to if so desired. As shown, the parts 3 are each provided with projecting parts 6 75 having inclined or cam faces adapted to cooperate with the faces on 4. There may be any number of series of cooperating parts 4 and 6; as shown there are two series arranged one adjacent each end of the parts 3, 80 as most clearly shown in Fig. 1. I have shown pins 7 carried by the parts 3 and projecting into the spaces 4, and in this connection it may be mentioned that it is immaterial whether the space 5 is arranged on 85 part 1 or part 3, this depending upon which part carries the pins 7. The pins 7, engaging between the parts 4, tend to prevent relative rotation of the parts 3 on the part 1. Obviously, as parts 3 are moved toward the support or bracket 2, the arbor parts 3 are 90 expanded or moved outwardly from the axis of the shaft 1, thereby increasing the diameter of the same, movement in the opposite direction permitting their contracting, thereby reducing the diameter of the arbor at the exterior parts 3.

The arbor parts may be maintained on the shaft 1 in any desired manner. As shown, a collar 8 is arranged on the shaft, the same 100

being formed with flange 8' of a size to fit the arbor when in its expanded position and prevent further expansion at that end thereof. A spring 9 bearing against collar 10 on the shaft tends to maintain the part 8 in engagement with the arbor, as well as to move the entire arbor on the shaft toward the free end. Arranged on the opposite end of the shaft 1 is a member 11, this being preferably constructed to engage the threaded end 12 of the shaft. Member 11 is provided with a flange 13 arranged to fit over and engage the flange 14 on the parts 3 and limit the expansion at that end. Referring to Fig. 15, it will be noted that one or more of the parts 3 are provided with slots 15, and I have shown members 16 mounted on the arbor, the number of these depending upon the size of the strips to be wound. I have also 20 shown the parts 3 provided with an internal rib 18, which tends to strengthen the parts.

In using the device, assuming that strips are to be wound in coils, the same being of widths substantially equal to the distance 25 between the plates 16, it may be mentioned that the material may be drawn directly from the machine, cutting the strips from a large piece or plate. The extreme free 30 ends of the strips may be inserted in the desired slot 15, the plates 16 being pushed up so as to form spaces for the coils, the same serving to feed the strips evenly on the arbor and maintaining the coils flat at their 35 faces. The arbor is in its expanded position substantially as shown in Fig. 1. If now shaft 1 is driven, the strips will be wound on the arbor until the desired amount of material is coiled or rolled. If the end of the strip is reached or the strip severed, the 40 coils will be contained on the arbor. The part 11 may then be turned on the threaded end 12 of the shaft so that the arbor may be moved away from the support 2, spring 9 tending to push the whole arbor toward 45 the end of the shaft. A slight movement of the arbor parts on the shaft 1, however, moves the parts 6 bearing on the faces of parts 4. Owing to the inclination of the faces between the parts, the parts 3 may 50 then be contracted thereby relieving the pressure caused by the winding of the coil tightly on the arbor. The movement of the parts 3 being slight to permit the contraction, flanges 8' and 13 will remain in engagement with the arbor parts, maintaining 55 them assembled. The plates 16 and coils of material may then be readily removed from the arbor by sliding the same over the end. Part 11 may then be turned up, again expanding the arbor to its winding adjustment. The recesses 6' permit a certain 60 amount of clearance of the pins 7.

It will thus be obvious that the coils may be readily removed from the arbor without 65 difficulty and in but a moment's time, and

without the slightest danger of telescoping, as it may be termed, or disarranging the rolls or coils. The device permits the material to be very tightly and uniformly wound and all of uniform size. 70

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned. 75

What I claim as new and desire to secure 80 by Letters Patent is:

1. A winding arbor, comprising in combination, a drive member, an expandable arbor member carried thereby and removable longitudinally thereof, means always entirely within the periphery of said arbor for radially expanding it, and yieldably held means exteriorly of said arbor member for limiting the expansion of said arbor member. 85

2. A winding arbor, comprising in combination, a drive shaft member, an arbor shell of a plurality of circumferentially arranged sections removably carried thereby, axially spaced cam faces projecting inwardly from said arbor sections, cam faces projecting outwardly of said shaft and cooperable with first said cam faces to prevent independent rotational movement between said arbor and shaft, 95 means for moving one of said shaft members longitudinally of the other to radially expand said shell member, and a rib on said arbor shell intermediate its cam faces to reinforce said shell and limit the radial inward movement thereof. 100

3. A winding arbor, comprising in combination, a drive shaft member, an arbor member of a plurality of circumferentially arranged sections surrounding said drive member and carried thereby, cooperating cam faces on both said members, means for adjustably moving said arbor sections longitudinally of said shaft to engage said cam faces and expand said arbor member, means longitudinally movable on said shaft and enclosing the ends of said arbor sections for limiting said expansion, and means for yieldably pressing one of said end-enclosing means axially against said arbor member to 115 releaseably hold said arbor member within the other end-enclosing means. 120

4. A winding arbor, comprising in combination, a rotary drive shaft member, an arbor shell of a plurality of circumferentially arranged sections removably carried thereby, axially spaced cam faces projecting inwardly from said arbor sections, axially spaced cam faces projecting outwardly of said shaft and cooperable with said arbor 130

cam faces, the cam faces on one of said shaft members having a longitudinal slot, the cam faces on the arbor section having a pin projecting therefrom engageable in said slot to prevent independent rotational movement between the arbor and shaft, means for adjustably moving one of said members longitudinally of the other to radially expand said shell member, and a rib on said 10 arbor shell intermediate its cam faces to re-

inforce said shell and limit the radial inward movement thereof.

In testimony whereof I have hereunto signed my name in the presence of two subscribing witnesses.

CHARLES D. DALLAS.
